KNIFE FOR EAR OPERATIONS

Ricardo J. Heros, Memphis, Tenn., assignor to Richards
Manufacturing Co., Memphis, Tenn.

Filed Sept. 15, 1972, Ser. No. 289,679

Term of patent 7 years

Int. Cl. D24—02

U.S. Cl. D83—12 R

FIG. 1

FIG. 2

FIG. 3

FIG. 4

FIG. 5

FIG. 6

FIG. 7

FIG. 1 is a side elevational view of the knife for ear operations, showing my new design.

FIG. 2 is a top plan view thereof.

FIG. 3 is a side elevational view thereof of the opposite side from that shown in FIG. 1 and with the knife having been turned 180° about its longitudinal axis from the position shown in FIG. 1.

FIG. 4 is a bottom plan view thereof.

FIG. 5 is an end elevational view thereof.

FIG. 6 is an end elevational view thereof from the opposite end from that shown in FIG. 5.

FIG. 7 is a cross sectional view taken as on the line VII—VII of FIG. 1.

I claim:

The ornamental design for a knife for ear operations, as shown.
